[57] **CLAIM**

The ornamental design for a basketball backboard cover, as shown and described.

DESCRIPTION

FIG. 1 is a perspective view of a basketball backboard cover showing the new design, the basketball hoop shown in broken lines is for illustrative purposes only and forms no part of the claimed design.

FIG. 2 is a top plan view thereof.

FIG. 3 is a bottom plan view thereof.

FIG. 4 is a front elevational view thereof.

FIG. 5 is a rear elevational view thereof.
FIG. 6 is a side elevational view thereof; and,
FIG. 7 is an enlarged rear elevational view thereof, with the rear left bottom and the rear right bottom in alternate positions.

The broken line showing on the basketball backboard cover in FIGS. 1, 4, 5 and 7 is representative of conventional stitching.
